(57) **CLAIM**

I claim the ornamental design for a reflective pattern on garment, as shown and described.

DESCRIPTION

FIG. 1 is a perspective view of a reflective pattern on garment.

FIG. 2 is a front elevation view thereof.

FIG. 3 is a rear elevation view thereof.

FIG. 4 is a first side or right side elevation view thereof.

FIG. 5 is a second side or left side elevation view thereof.

FIG. 6 is a top plan view thereof.

FIG. 7 is a bottom plan view thereof.

FIG. 8 is a detail view thereof taken from detail 8 of FIGS. 1, 2, and 3; and,

FIG. 9 is a detail view thereof taken from detail 9 of FIGS. 1 and 2.

Those features shown in solid lines in FIGS. 1, 2, 3, and 8 depict a reflective surface, which can further be retroreflective or mirror reflective. Those features shown in broken lines form no part of the claimed design. More specifically, the even broken lines illustrate unclaimed portions of the garment, each square shown in dot-dash broken lines illustrates an unclaimed boundary of each of a plurality of areas of the garment shown enlarged in the details of FIGS. 8 and 9, and each circle shown in dot-dash broken lines and encircling a claimed area of the garment—defining a pattern of solid lines in FIG. 8 and defining an absence of solid lines in FIG. 9—illustrates an unclaimed boundary of the claimed design.

1 Claim, 5 Drawing Sheets
